(57) **CLAIM**

The ornamental design for an air conditioner, as shown and described.

DESCRIPTION

FIG. 1 is a front/right-side/top perspective view of a air conditioner showing our new design;

FIG. 2 is a front-side elevational view thereof;

FIG. 3 is a left-side elevational view thereof;

FIG. 4 is a right-side elevational view thereof;

FIG. 5 is a top-side elevational view thereof; and,

FIG. 6 is a bottom-side elevational view thereof.

The broken lines showing of the air conditioner is for illustrative purpose only and form no part of the claimed design.
